UNITED STATES PATENT OFFICE.

HERMANN WYDLER, OF BERNE, SWITZERLAND, ASSIGNOR TO THE FIRM OF SAUSER S. A., OF SOLEURE, SWITZERLAND.

CONTROLLING DEVICE FOR STARTING AND DETERMINING THE QUANTITIES TO BE DELIVERED BY A LIQUID RAISING APPARATUS PLACED AT SOME DISTANCE FROM SAID DEVICE.

Application filed October 7, 1925, Serial No. 61,148, and in Switzerland October 10, 1924.

The present invention relates to a device for controlling a liquid raising and measuring apparatus established at some distance from said device and consists in a graduated disk 5 mounted in a casing and held in position by a ratchet stop-device against the action of a spring, a jack provided with a handle serving as means for adjusting said disk to the desired number of measuring vessels and for 10 starting the apparatus by uncoupling the disk from the jack and by coupling this latter with a slide, the disk being returned stepwise into its zero position according to the number of the delivered vessels whereupon the apparatus is stopped and the jack restored again 15 into its initial coupled position.

In the annexed drawing one working form of the device is represented as an example.

Fig. 1 shows the working position of parts 20 and is a section on line I—I of Fig. 2 which is a rear view.

Fig. 3 is a section on line III—III of Fig. 1 seen from the left and with the wall plate 42 removed.

25 Fig. 4 is a similar section seen from the left on line IV—IV of Fig. 1.

Fig. 5 represents a detail and Fig. 6 a part of Fig. 1, showing the initial position of parts, that is the position of rest.

30 Fig. 7 is a partial section on line VII—VII of Fig. 2.

The principal portion of the controlling device according to the present invention is enclosed within a casing 1 closed on one side by a hood 3 and on the other side by a plate 41 which is secured to the back of a wall-plate 42 while on the front side of said wall-plate are disposed the adjusting parts comprising a graduated rotatable disk 4, a conical jack 14 inserted into said disk and a cover 2 of said disk provided with a window 40 showing only a part of said graduation. Said disk is operated upon by a spiral spring 5 which is attached at one end to the wall plate 42 and at the other end to the disk's hub and is bent so as to turn the cover in an anti-clockwise sense. A pawl 35 pivotally mounted within a hollow of said disk's hub (Fig. 3) engages under the effect of a spring 34 the inner teeth of a ratchet-ring 6 the other teeth of which are engaged by a rocking-lever 7. An initial bend is given to spring 5 so that pawl 35 is constantly trying to turn the ring

6 in an anti-clockwise sense. But the turning of this ring in this direction is prevented by a 55 rocking-lever 7 while a return movement of the ring is prevented by the pawls 8 and 9. The pitch of the inner teeth of ring 6 is half that of the outer teeth. If rocking-lever 7 mounted on a square of axis 10 is oscillated 60 its arms will act alternately so as to allow at each stroke and under the effect of spring 5 a turning movement of ring 6 for one tooth at a time. Now the axis 10 of lever 7 is moved by means of an arm 11 kept in contact with a 65 piston 12 by a spring 32, said piston being operated upon by a series of balls in the ball-tube 13 which is leading to the liquid raising apparatus established at any distance from our device. The disk 4 having a central conical boring is mounted on a conical jack 14 which is serving as a coupling means between disk and jack and extends to the outside of the cover 2 where it is provided with an adjusting handle or knob 15. The jack being 70 hollow serves also as a guide for the hollow end of a cylindrical slide 16 which is extended through the center of the device into the hood 3. Said hollow end encloses a strong helical spring 17 which bears with one end on slide 75 16 and with the other end on jack 14 so as to keep the latter during the position of rest or readiness coupled with the disk 4.

A two armed trigger 19 (only shown in Figs. 1 and 6) is pivotally mounted within a 85 slot 18 (Fig. 7) of slide 16 and extends in the operative position of parts as shown in Fig. 1 with a hook 20 and with a nose 21 to the outside of the path of slide 16. In this position hook 20 engages under the effect of a 90 spring 36 the inner edge of a sleeve 22 which is screwed to the end of jack 14 and maintains thereby the coupling between jack and slide so that the effect of spring 17 is nullified during the operative position of parts. 95

As uncoupling means between jack and slide there is a small shaft 23 having two catches 24 and 25 (Figs. 1, 4 and 6) whereof catch 24 under the effect of a spring 34 bears on the edge of a rim 26 and engages in the 100 position of rest of the device the notch 27 in said rim. In the coupled state of jack and slide that is when catch 24 is on the edge of rim 26, the other catch 25 is in contact with nose 21 of the trigger so that whenever catch 105 24 snaps into the notch 27 catch 25 will push

the trigger 19 inwards and disengage hook 20 from the rim of sleeve 22 and restore the effectiveness of spring 17 which will cause the uncoupling of jack and slide so that knob 15 retakes its initial position of rest.

5 A pin 29 (Fig. 5) embedded within an insulating block 33 which is fixed to slide 16 forms the contact member between two contacts 30 which are supported by a ring 31 10 of insulating material mounted between hood 3 and casing 1. This ring carries also the terminals of the electrical leads connected to the electro-motor of the liquid raising apparatus. The operating means between the ball-tube 13 and the liquid raising and measuring apparatus is not shown. It may consist 15 of an oscillating lever operated by the discharges of the measuring vessel, said lever moving the balls within tube 13 against the effect of the spring 32. When spring 28 has become effective knife 29 will be moved between the contacts 30 and the circuit of the motor will be completed whereby the liquid raising apparatus will be started. This contact 25 switch 29, 30 is only unipolar, but of course it could also be bipolar, then it would need four terminals.

The working of the apparatus is as follows:

10 In the initial position or the position of rest shown partly in Fig. 6 the parts are positioned as follows: Jack 14 is coupled by friction with disk 4 and spring 17 presses the slide 16 into the hood 3 so that the block 33 of insulating material bears on a rim of 15 said hood. The trigger 19 which is maintained in its disengaged position by sleeve 22 is partly introduced into an opening of 20 the hood 3 as shown in Fig. 6. Then the contacts 29, 30 are broken.

25 If a certain quantity of liquid which is of course always a multiple of the content of the measuring vessel has to be delivered knob 15 and therewith also jack 14 which under the effect of spring 28 is kept coupled like a wedge to the disk 4 is turned by hand if seen 30 from the front side in a clockwise sense for so many teeth as there are measuring vessels to be delivered. By this operation notch 27 will be withdrawn from catch 24 and this latter will bear on the surface of rim 26 so 35 that catch 25 will no more hinder the axial movement of jack 14. This jack is now pushed inwards by giving a tap on knob 15 causing hook 20 of trigger 19 to snap over 40 the inner edge of sleeve 22 (Fig. 1) thus coupling jack 14 with slide 16.

45 As the effect of spring 17 becomes nullified by this operation spring 28 will become effective and will move slide 16 so that pin 29 completes an electrical circuit between the contacts 30 said movement being limited by the insulating block 33 which is arrested by a partition wall of the casing 1 in order to bring nose 21 of the trigger 19 under the catch 25. The closing of the circuit sets

5 the motor of the measuring vessel to work. At each delivery of the measuring vessel the balls of tube 13 will move and piston 12 will oscillate arm 11 which will move shaft 10 and lever 7 so that under the effect of spring 70 5 the disk 4 will be moved stepwise tooth for tooth into its zero position. At this moment catch 24 snaps into the notch 27 and causes catch 25 to push trigger 19 which withdraws hook 20 from sleeve 22. By this uncoupling 75 of slide 16 from jack 14 spring 177 becomes effective again. Slide 16 will be pushed again into the position of Fig. 6 where the electrical circuit is interrupted and the liquid raising apparatus will be stopped and jack 14 will 80 be wedged again into disk 4 so as to be coupled therewith. Thus the initial position of parts or the position of rest has been restored again.

85 It has been supposed here that the operating means of the liquid measuring apparatus 85 be an electro-motor the circuit of which is under the control of the device according to the present invention.

This device however could also be employed if the operating means of the liquid 90 measuring apparatus is a hand pump. The slide 16 would in this case carry those members which allow or hinder the operating of said pump. This slide could for instance be adapted to cause the venting of the suction 95 conduit of said pump in order to prevent any liquid raising until the desired quantity has been adjusted on the new device.

Finally it could also be possible to combine the mechanical arrangement with the 100 electric arrangement.

What I claim is:

1. In a controlling device for starting and determining the quantities to be delivered by a liquid raising apparatus placed at some distance from said device and in combination, a casing of the controlling device established at some distance from said apparatus, an adjustable graduated disk having a conical boring and lodged within said casing, a spiral spring adapted to turn said disk in an anti-clockwise sense, a toothed ratchet ring surrounding said disk and a pawl as coupling means of disk and ring for movements in an anticlockwise direction, pawls capable of preventing a return movement of the ratchet ring, a rocking lever arranged so as to allow a moving of ring and disk stepwise, means rendering the movements of the rocking lever dependent on the discharges of the measuring vessels and a jack having a handle extended to the outside of the device and a conical shank fitting the hole of said disk and available as carrier means for adjusting the disk.

115 2. In a controlling device for starting and for determining the quantities to be delivered by a liquid raising apparatus placed at some distance from said device and in combination, a casing of the controlling device estab- 120 125 130

lished at some distance from said apparatus, means for establishing an operative communication between this device and said apparatus, electrical contacts on said casing, 5 an adjustable graduated disk having a conical boring and lodged within said casing, a jack with handle, having a hollow conical shank fitting the hole of said disk and available as adjusting means of the disk, a sleeve 10 fast to the end of said shank and provided with a free inner edge as rest for a trigger, a slide guided coaxially within said shank and carrying an electric contact pin, a strong spring capable of parting jack and slide as 15 means for coupling jack and disk and for keeping said contacts broken, a trigger device mounted on said slide and adapted to maintain the compressed state of said strong 20 spring and the coupled state between jack and slide and a weak spring at the free end of the slide as means for restoring the electric contacts and for coupling jack and disk after said trigger device is set.

3. In a controlling device for starting and 25 for determining the quantities to be delivered by a liquid raising apparatus placed at some distance from said device and in combination,

a casing of the controlling device established at some distance from said apparatus, an adjustable graduated disk having a conical 30 boring and lodged within said casing, a spiral spring adapted to turn said disk in an anticlockwise sense, a ratchet ring with internal and external teeth and surrounding said disk, a pawl pivoted on said disk and 35 engaged with said internal teeth of the ratchet ring, pivoted pawls on the casing engaging with said external teeth for preventing any return movement of said ring, a pivoted rocking lever adapted to engage said 40 external teeth so as to allow the ring to move only stepwise, a shaft rigidly connected to said lever, an arm fast to this shaft, a ball tube established between the casing and the measuring vessel of the apparatus as means 45 of transmitting the effect of each delivery of the measuring vessel to the controlling device, a piston in contact with the balls of said tube, guided within the casing and a spring 50 engaging said arm so as to assure the contact of said piston with the balls all substantially as shown and for the purpose set forth.

In testimony whereof I affix my signature.
HERMANN WYDLER.
